CLAIM

We claim the ornamental design for a spark plug extension, as shown and described.

DESCRIPTION

FIG. 1 is a perspective view of the spark plug extension;

FIG. 2 is a front view thereof;

FIG. 3 is a back view thereof;

FIG. 4 is a left view thereof.

FIG. 5 is a right view thereof.

FIG. 6 is a top view thereof; and,

FIG. 7 is a bottom view thereof.

The broken line portion of the figure drawings is included to show unclaimed subject matter only and forms no part of the claimed design.
